UNITED STATES PATENT OFFICE.

LOUIS G. LARSEN, OF BRIDGEPORT, CONNECTICUT, ASSIGNOR, BY MESNE ASSIGNMENTS, TO COLUMBIA GRAPHOPHONE MANUFACTURING COMPANY, OF BRIDGEPORT, CONNECTICUT, A CORPORATION OF DELAWARE.

AUTOMATIC STOP.

Application filed November 22, 1916. Serial No. 132,883.

To all whom it may concern:

Be it known that I, LOUIS G. LARSEN, a citizen of Denmark, and a resident of Bridgeport, Connecticut, have invented a new and useful Improvement in Automatic Stops, which invention is fully set forth in the following specification.

This invention relates to stop mechanism, and particularly to stop mechanism for use on sound-recording or reproducing machines to effect the cessation of movement of the record tablet supporting element upon the completion by the reproducing or recording member of its traverse of the aforesaid record tablet.

It is an object of this invention to provide a stop mechanism of the character described, wherein the stopping of the sound record supporting or rotating element shall not take place after the starting of the motor until such rotating element has made a predetermined number of revolutions, thereby, when said stopping mechanism is applied to a sound-reproducing machine, insuring an adequate time to properly position the needle of the reproducing member in the first groove of the record without danger of premature stopping of the machine.

In my application Serial No. 72,774, filed January 18, 1916, Patent No. 1,405,046, January 31, 1922, I have disclosed an automatic stop mechanism wherein oscillatory members are respectively moved by the rotating and traveling elements, and wherein means are provided for so connecting such members upon the cessation of movement of the said traveling element as to effect the actuation of the stop mechanism. It is an object of this invention to improve the construction described and claimed in my prior application, particularly by the provision of means whereby premature stopping of the record is prevented, as heretofore pointed out.

A still further object of this invention is to provide a stop mechanism which shall be simple in construction, easy to manufacture, and efficient and certain in operation. Other objects will appear as the description proceeds.

Stated broadly, the invention comprises, in

combination with a traveling element and a rotating element, means as a brake or a switch to stop said rotating element upon the stopping of said traveling element, and timing mechanism whereby said rotating element must pass through a predetermined number of revolutions before the stopping means may become effective.

Stated somewhat more specifically, the invention comprises, in combination with the aforesaid rotating and traveling elements, members moved by said elements respectively and preferably oscillated thereby, said members being shown as moving as a unit during the normal movement of the traveling element; means whereby upon the stopping of said traveling element said members cooperate to effect the stopping of said rotating element, one of such members preferably being supplementally moved into operative engagement with a stop device; and means in the form of timing mechanism, preferably controlled by the rotating element for preventing said members assuming the aforesaid cooperative relationship to effect the stopping of the rotating element prior to a predetermined number of revolutions of such element.

The invention is capable of a variety of mechanical expressions, one of which is shown on the accompanying drawings, but it is to be expressly understood that the drawings are for purposes of illustration only, and are not to be construed as definitive of the limits of the invention, reference being had to the appended claims for that purpose.

Referring to the drawings, wherein the same characters of reference designate corresponding parts in the several figures,

Fig. 1 is an elevation of a sound-reproducing machine embodying the present invention, parts being shown in section;

Fig. 2 is a plan view of a sound-reproducing machine embodying the present invention with portions of the tone-arm, turn-table and record broken away for sake of clearness;

Fig. 3 is a perspective of a stop mechanism embodying the present invention, showing in separated relation the several

parts of the frictional connection between the tone-arm or traveling element and the member moved thereby:

Fig. 4 is a fragmentary detail plan of a part of the stop mechanism; and

Fig. 5 is a perspective view showing certain of the elements of Fig. 4 in separated relation.

Referring in detail to the drawings, 10 represents the frame of any suitable motor such, for example, as is conventionally employed in sound-reproducing or recording machines. 2 represents the usual turn-table spindle driven by said motor, 3 the turn-table, and 4 a record supported thereby, said spindle, table or record constituting a rotating element. 5 illustrates any suitable sound-box supported by a suitable tone-arm 6, said tone-arm in turn being shown as rotatably mounted in a hollow bracket or thimble 7, (see Fig. 1), and communicating with a suitable amplifier (not shown). While the drawings illustrate a tone-arm which is turned downwardly at its outer end to communicate with a concealed horn, it is to be expressly understood that the invention is in no respects restricted to any particular type of sound-reproducing machine, since by suitable modification the invention could be applied with equal facility to a machine wherein the horn is disposed above the turn-table and record tablet. Said sound-box and its supporting element or tone-arm constitute a traveling element. 35 Frictionally connected with the traveling element is an arm 8 adapted to be moved by the said element as it traverses the rotating element during the normal operation of the machine. Any suitable friction connection 40 may be employed between said arm 8 and the tone-arm. In the form shown, the depending portion 9 of said traveling element, which is received within the aforesaid bracket or thimble 7, is slightly reduced in exterior diameter at its lower end, as illustrated at 10, said reduced portion being provided with a key 11. Mounted on the reduced portion 10, with a key-slot receiving the key 11, and engaging the shoulder between the aforesaid portions 9 and 10, is a washer 12, preferably of metal, between which and a second similar washer 13, also received upon said key, is a spiral spring 14. The arm 8 is mounted, with the interposition of frictional washers 15 and 16, preferably of felt, between said washer 13 and a bayonet nut 17 provided on its inner face with one or more lugs 18 to be received in bayonet slots 19 at the lower extremity of the reduced portion 10. The expansion of the spring 13 causes the arm 8 to be frictionally gripped between the felt washers 15 and 16, but the arm 8 may be moved independently of the depending por-

tion of said traveling element and the metal washers keyed thereto. If desired, the thimble or bracket 7 may be extended downwardly so as to constitute a housing for the mounting of the arm 8, as illustrated at 20, in which event said housing 70 will be apertured, as shown at 21, and an annular end cap may be provided, as illustrated at 22.

Mounted on the frame of the motor by any suitable form of pivotal mounting, as shown at 23, is a lever member 24, downwardly bent at its outer end and provided with a forked extremity as shown at 25. Arm 8, which is bent downwardly to clear the top wall of the cabinet, is bent upwardly at its inner end and received between the furcations of said fork, as shown at 26. Also pivotally mounted upon the frame of the motor, as by a pivot-screw 27, is an arm 28 angularly bent at its inner end, as shown, to provide a toe 29. Mounted on the motor frame is a gear 30, the teeth of which mesh with the teeth of a gear 31 on the turn-table spindle 2, such teeth being desirably cut directly in said spindle. Carried by the gear 30 and rotatably fixed with respect thereto is a cam 32 adapted to engage the aforesaid toe 29. To maintain said toe in operative engagement with said cam 32, whereby the arm 28 shall oscillate as the cam rotates, a spring 33 is connected to said arm 28 at one end and anchored to a pin 33' on the motor frame. Arm 28 is provided with an upstanding pin 34, preferably in a lug projecting laterally from said arm, whereby so long as lever 24 is urged into contact with pin 34 by the normal movement of the traveling element, said lever will partake of the oscillatory movement imparted to arm 28 by cam 32.

Also mounted upon pivot-screw 27 is a second arm or contact member 35. Washers 36 are desirably interposed between this arm and the motor frame and arm 28, as well as between the latter arm and the head of screw 27. Arm 35 is bent angularly in two directions, and carries upon its upper face, by preference adjustably with respect thereto, a contact element 37 having an upturned lug 38 intersecting the plane of movement of lever 24. Adjustment of the contact element with respect to arm 35 may be provided in any suitable way, as by the use of an elongated slot 39 in such element and screws 40 extending through said slot and securing said element fixedly in its adjusted position. As shown, a leaf-spring 41 is also preferably provided on such contact element as by attachment to the upstanding lug 38 and bears at its outer end upon the upper face of lever 24.

Means are provided for operatively connecting lever 24 and arm 28 whereby oscil-

lation of the latter will move the former into operative engagement with the contact arm heretofore described. As shown, a pair of upstanding lugs 42 is provided at one side 5 of the arm 28, and pivotally supported between such lugs is a pawl 43 having a down-turned nose 44 adapted to drop at the proper time into an elongated slot 45 in the lever 24.

While any suitable stop mechanism may 10 be employed for stopping the rotation of the rotating element, the embodiment of the invention shown on the drawings comprises a vertically movable plunger 46 carrying at its lower end a friction pad 47 for engagement with the usual governor disk 48. Plunger 45 is provided with a groove extending around the same adjacent its upper end, as illustrated at 49, and received within this groove is a stop-releasing lever 50 loosely 15 pivoted to the motor frame at 51 and provided at its outer end with a manual operating means, as a press-button 52 extending through the cabinet top into operative engagement therewith. Mounted on the stop-releasing lever 50 is a leaf-spring 53 bearing at one end against the motor frame, as shown at 54, and normally tending to depress the brake-plunger into stopping engagement with the governor disk. The 20 outer end of contact arm 35 is operatively related to said brake-plunger 46, and is drawn into the annular groove 49 by spring 55 when said groove is elevated into the plane of said arm. Spring 55 is attached at 25 one end to said arm 35, and at its opposite end is anchored to a pin 56 projecting upwardly from the motor frame. Arm 35 is so mounted on the pivot screw 27 that its inner end 57 may have a slight vertical 30 movement. A stop 58 may desirably be provided to limit the downward movement of said arm and to support the same when it is not in engagement with the brake-plunger 46. Stops 59 may also be provided 35 to limit the lateral movement of the arm 35 and also, if desired, the toe constituting the extension of arm 28.

Means are provided whereby a predetermined number of revolutions of the turntable must occur before the elements moved by the traveling element and rotating element respectively shall assume such cooperative relationship that, upon the stopping of said traveling element, they will effect actuation of the stop mechanism. While a wide variety of devices might be employed to accomplish this end, the embodiment shown comprises means for preventing pawl 43 from prematurely engaging in slot 45, and means for actuating the first said means, and controlled by the rotation of the turntable spindle, to admit of such engagement after a predetermined number of revolutions of said spindle. To this end pawl 43 is 40 provided with a depending lug 60, and ro-

tatably mounted on the arm 28 is a ratchet 61 provided with a concentric slot 62, said ratchet 61 being so positioned as, at the proper times, bring the said slot or the imperforate portion of the ratchet into operative relationship with the depending lug. To maintain the ratchet in such a position that the imperforate portion of the ratchet normally engages the depending lug 60 and holds the pawl elevated, and furthermore to 45 return the ratchet to such position after rotation therefrom, a spring 63 is attached at one end to the arm 28 and at its other end to said ratchet. The ratchet is provided through a portion of its periphery with a predetermined number of teeth 64, and to 50 advance the ratchet, tooth by tooth, from that position in which it is normally held by spring 63, a pawl 65 is mounted on the motor frame and provided with a resilient, inwardly bent end 66 adapted to engage said teeth 64 during movement of the arm 28 in one direction and rotate the ratchet through a distance equal to the space between adjacent teeth, and, during movement 55 of said arm in the opposite direction, to slide into engagement with succeeding teeth to again advance the ratchet upon the return of said arm. To prevent return of the ratchet to initial position under the influence of spring 63, while end 66 of pawl 65 is sliding into engagement with the succeeding teeth, a second pawl 67 is pivotally mounted at 68 on a lug projecting laterally from the arm 28, said pawl being provided 60 at one end with a nose 69 adapted to snap into engagement with the teeth of said ratchet and maintain the ratchet in the position to which it has been advanced by pawl 65. Pawl 67 is resiliently urged in a direction to engage its nose 69 with the ratchet by a spring 70 connected at one end to the pawl and bearing at its opposite end against the side of arm 28. To release pawl 67 65 from the ratchet, so as to permit spring 63 to restore the ratchet to initial position in preparation for the next actuation of the timing mechanism, a lever 71 is pivotally mounted on the motor frame at 72, said lever having an inwardly turned end 73 projecting into proximity to the contact member 35, and, at its opposite end, an upstanding lug 74 in which is adjustably mounted a contact screw 75 in the path of oscillation of a depending lug 76 on pawl 67. 70 To provide for the easy and gradual movement of the depending lug 60 into and out of the concentric slot 62, the edge of said slot over which the lug will travel is inclined or provided with a camming tongue, as shown 75 at 77. Lever 24 is preferably cut away at one edge, as shown at 78, to enable the engagement of depending lug 60 with the face of ratchet 61.

In operation, assuming the motor to be 80

stationary and the parts in the position illustrated in Fig. 2, the operator to start the machine will depress button 52, which will depress the outer end of lever 50, raising the inner end thereof against the tension of spring 54. The inner end of this lever, owing to its engagement in groove 49 of brake-plunger 46, will elevate the latter, freeing the governor disk 48 and enabling the motor 10 to start. When said plunger is raised to such a position that groove 49 is brought into the plane of contact member 35, the inner angularly bent end 57 thereof will be drawn by spring 55 into said groove, locking the 15 plunger in its upper position. The tone-arm, as it travels across the turn-table, will, owing to the frictional connection between its extremity and arm 8, tend to rotate said arm in a clockwise direction. The effect of 20 this tendency to rotation will be to move lever 24 about its pivot 23, owing to the upwardly directed extremity 26 of arm 8 engaging in the forked extremity 25 of said lever, urging said lever into engagement with 25 pin 34. As the turn-table spindle 2 rotates, cam 32 is rotated by the interposed gearing 30 and 31, cam 32 producing an oscillation of arm 28 about pivot 27 owing to the coaction of the cam and toe 29. Spring 33 maintains toe 29 resiliently in engagement with 30 said cam, whereby the arm partakes of the oscillation defined by the contour of the cam. As arm 28 rotates in a clockwise direction, pin 34 will engage the side of lever 24, moving 35 the same in a clockwise direction, and through the engagement of said lever with arm 8, moving the latter in an opposite direction against the tendency of rotation produced by normal movement of the tone-arm 40 across the record, it being understood that, owing to the frictional connection between the arm 8 and said tone-arm, there will be a slipping of the former. During rotation of arm 28 in an anti-clockwise direction, arm 8 45 under the influence of the tone-arm will rotate lever 24 in an anti-clockwise direction, maintaining said lever in engagement with the pin 34. This will continue so long as the tone-arm traverses the record on the turn-table. 50

As soon as the turn-table begins to rotate and arm 28 to oscillate, ratchet 61 will be advanced step by step, as upon each movement of arm 28 in an anti-clockwise direction the inner end 66 of pawl 65 in engagement with a tooth 64 of said ratchet will advance the same through a distance equal to the space between adjacent teeth against the tension of spring 63. During movement of arm 28 55 in a clockwise direction, pawl 67 will retain the ratchet in the position to which it has been advanced and pawl 66 will slide into engagement with the next tooth of the ratchet. Thereby, during a predetermined 60 number of revolutions of the turn-table spin-

dle, the ratchet will be advanced step by step, until the last tooth has been engaged and advanced by pawl 65. At this time concentric slot 62 has been advanced under the depending lug 60, enabling pawl 43, which partakes of the oscillation of arm 28, to be lowered through a small angle until nose 44 rides upon the upper surface of lever 24. Pawl 43 has now assumed such relation to the parts that, upon stopping of the tone-arm, the stopping of the motor may be effected. 75

Upon the stopping of the tone-arm, no further tendency will be exerted through arm 8 to rotate lever 24 in an anti-clockwise direction. Accordingly, upon the next advancement clockwise of said lever by the arm 28, lever 24 will remain in the position to which it is advanced by engagement of pin 34 with said lever, and during the movement of the arm 28 in an anti-clockwise direction the pawl 43 will slide over the face of lever 24 until its nose 44 drops into slot 45. During the subsequent movement of the arm 28 in a clockwise direction, pawl 44 will 90 draw lever 24 in a clockwise direction, said lever during this supplemental movement engaging the upstanding lug 38 on contact member 35, moving the latter about its pivot 27 and withdrawing its extremity 57 from 95 groove 49 against the tension of spring 55. Thereupon, spring 54 through lever 50 will depress brake plunger 46, re-engaging the brake-pad 47 with the governor disk 48 and stopping the motor. As lever 24 is moved 100 into operative engagement with the contact member 35 and the latter is rotated about its pivot 27 in a clockwise direction, lever 71 is engaged by the contact member and rotated slightly in a clockwise direction engaging 105 contact screw 75 with depending lug 76 on the end of pawl 67, thereby rotating the latter in a clockwise direction against the tension of spring 70 and withdrawing the nose 69 of the pawl from engagement with the 110 ratchet 61. The latter is thereupon rotated to its initial position by spring 63, the inclined edge of cam tongue 77 engaging depending lug 60 on pawl 44 and camming the pawl out of engagement with lever 24, until 115 said lug rides upon the face of the ratchet where it is prevented from again assuming operative relationship with the lever until, following the predetermined number of revolutions of the turn-table spindle, the ratchet 120 is again advanced to a position wherein lug 60 may drop into the concentric slot 62.

While the illustrated embodiment has been described with considerable particularity, it is to be expressly understood that the invention is not to be restricted to the embodiment shown and described, as the same is capable of a variety of mechanical expressions, some of which will readily suggest themselves to those skilled in the art, while cer- 130

tain parts thereof are susceptible of use without other parts thereof. Therefore, reference is to be had to the claims hereto appended for a definition of the limits of the 5 invention.

What is claimed is:

1. In combination, a traveling element, a rotating element, stop mechanism for the rotating element, means for actuating the stop mechanism upon the stopping of the traveling element, and means rendering the said means incapable of actuating the stop mechanism prior to a pre-determined number of revolutions and at the beginning of 15 rotation of the rotating element.

2. In combination, a traveling element, a rotating element, stop mechanism for the rotating element, means for actuating the stop mechanism upon the stopping of the traveling element, and timing mechanism for maintaining said means incapable of actuating the stop mechanism at the beginning of rotation of the rotating element.

3. In combination, a traveling element, a rotating element, stop mechanism for the rotating element, means for actuating the stop mechanism upon the stopping of the traveling element, means controlled by the rotating element for rendering the first 30 named means inoperative to actuate the stop mechanism prior to a predetermined number of revolutions at the beginning of rotation of the rotating element.

4. In combination, a traveling element, a rotating element, stop mechanism for the rotating element, means for actuating the stop mechanism upon the stopping of the traveling element, and timing mechanism, controlled by the rotating element, for maintaining 40 said means inoperative to actuate the stop mechanism at the beginning of rotation of the rotating element.

5. In combination, a traveling element, a rotating element, stop mechanism, oscillating means moved by the traveling element, and oscillating means moved by the rotating element, means whereby, upon the stopping of the traveling element, both the oscillating means are adapted to co-operate 50 with each other to render the stop mechanism operative, and timing mechanism adapted to prevent such co-operation.

6. In combination, a traveling element, a rotating element, stop mechanism, oscillating means moved by the traveling element, and oscillating means moved by the rotating element, means whereby, upon the stopping of the traveling element, both the oscillating means are adapted to co-operate 60 with each other to render the stop mechanism operative, and means adapted to prevent co-operation prior to a pre-determined number of revolutions of the rotating element.

65 7. In combination, a traveling element, a

rotating element, stop mechanism for the rotating element, a member moved by the traveling element, a member moved by the rotating element, means whereby, upon the stopping of the traveling element, both of 70 such members are adapted to co-operate with each other to render the stop mechanism operative, and means whereby the rotating element, at the beginning of rotation, must pass through a pre-determined number of 75 revolutions before the members can so co-operate.

8. In combination, a traveling element, a rotating element, stop mechanism for the rotating element, means for actuating the stop mechanism upon the stopping of the traveling element, and timing mechanism whereby the rotating element, at the beginning of its rotation, must pass through a pre-determined number of revolutions before 85 said means may be rendered operative to actuate the stop mechanism.

9. In combination, a traveling element, a rotating element, stop mechanism for the rotating element, a member moved by the traveling element, a member moved by the rotating element, means controlled by the rotating element whereby, upon the stopping of the traveling element, both of such members are adapted to co-operate with each 90 other to render the stop mechanism operative, and means whereby the rotating element, at the beginning of its rotation, must pass through a pre-determined number of 95 revolutions before the members can so co-operate.

10. In combination, a traveling element, a rotating element, stop mechanism for the rotating element, means for actuating the stop mechanism upon the stopping of the traveling element, and timing mechanism whereby the rotating element, at the beginning of its rotation, must pass through a pre-determined number of revolutions before 105 said means may be rendered operative to actuate the stop mechanism.

11. In combination, a traveling element, a member moved thereby, a rotating element, a member moved by said rotating element and operatively connected to said first-named member to move the same in one direction, stop mechanism, means whereby upon the stopping of said traveling element said second-named member moves said first-named member into operative engagement 115 with said stop mechanism, and means to prevent operation of said last-named means prior to a predetermined number of revolutions of said rotating element.

12. In combination, a traveling element, a member controlled by the traveling element, a rotating element, a member controlled by the rotating element, connections whereby said members are maintained in coacting 125 relation during the normal movement of said 130

traveling element, stop mechanism, means for moving said first-named member into engagement with said stop mechanism upon the stopping of said traveling element, and 5 means to prevent operation of said last-named means prior to a predetermined number of revolutions of said rotating element.

13. In combination, a traveling element, a member controlled by the traveling element, 10 a rotating element, a second member controlled by the rotating element, connections whereby said members are maintained in co-acting relation during the normal movement of said traveling element, stop mechanism, 15 means whereby said second member moves said first member into operative engagement with said stop mechanism upon the stopping of said traveling element, and means to prevent operation of said last-named 20 means prior to a predetermined number of revolutions of said rotating element.

14. In combination, a traveling element, a member controlled by the traveling element, a rotating element, a second member controlled by the rotating element, connections whereby said members are maintained in co-acting relation during the normal movement of said traveling element, stop mechanism, means for moving said first member 25 into operative engagement with said stop mechanism upon the stopping of said traveling element, and timing mechanism for controlling the operation of said last-named means.

30 15. In combination, a traveling element, a member moved thereby, a rotating element, a member moved by said rotating element and operatively connected with said first-named member to move the same in one direction, stop mechanism, means whereby upon the stopping of said traveling element said second-named member moves said first-named member into operative engagement with said stop mechanism, and timing mechanism for controlling the operation of said 35 last-named means.

16. In combination, a traveling element, a member frictionally driven from and continuously in operative relation with the 40 traveling element, a rotating element, a second member continuously in operative relation with the rotating element, operative connections between said members, stop mechanism, means for moving said first member into operative engagement with said stop mechanism upon the stopping of said traveling element, and means to prevent the 45 operation of said last-named means prior to a predetermined number of revolutions of said rotating element.

50 17. In combination, a traveling element, a member moved thereby, a rotating element, a second member moved by said rotating element, connections between said members whereby said second member moves said 55

first member in one direction during the normal travel of said traveling element, a contact member, means for stopping said rotating element controlled by said contact member, means whereby said second member moves said first member into operative engagement with said contact member upon the stopping of said traveling element, and timing mechanism to control the operation of said last-named means. 70 75

18. In combination, a traveling element, a member moved thereby, a rotating element, a second member moved by said rotating element, connections between said members whereby said second member moves said 80 first member in one direction during the normal travel of said traveling element, a contact member, means for stopping said rotating element controlled by said contact member, means whereby said second member moves said first member into operative engagement with said contact member upon the stopping of said traveling element, and means to prevent the operation of said last-named means prior to a predetermined number of revolutions of said rotating element. 85 90 95

19. In combination, a traveling element, a member moved thereby, a rotating element, a second member moved by said rotating element, connections between said members whereby said second member moves said first member in one direction during the normal travel of said traveling element, a contact member, means for stopping said rotating element controlled by said contact member, a latch carried by said second member and adapted to move said first member into operative engagement with said contact member upon the stopping of said traveling element, and means to prevent the operation of said latch prior to a predetermined number of revolutions of said rotating element. 100 105 110

20. In combination, a traveling element, a member moved thereby, a rotating element, a second member moved by said rotating element, connections between said members whereby said second member moves said first member in one direction during the normal travel of said traveling element, a contact member, means for stopping said rotating element controlled by said contact member, a latch carried by said second member and adapted to move said first member into operative engagement with said contact member upon the stopping of said traveling element, and timing mechanism to control the operation of said latch. 115 120 125

21. In combination, a traveling element, a member moved thereby, a rotating element, a second member moved by said rotating element, connections between said members whereby said second member moves said first member in one direction during the normal travel of said traveling element, 130

- a contact member, means for stopping said rotating element controlled by said contact member, a latch carried by said second member and adapted to move said first member into operative engagement with said contact member upon the stopping of said traveling element, a ratchet controlling the operation of said latch, and means for rotating said ratchet.
22. In combination, a traveling element, a member moved thereby, a rotating element, a second member moved by said rotating element, connections between said members whereby said second member moves said first member in one direction during the normal travel of said traveling element, a contact member, means for stopping said rotating element controlled by said contact member, a latch carried by said second member and adapted to engage and move said first member into operative engagement with said contact member upon the stopping of said traveling element, a ratchet for lifting and maintaining said latch out of engagement with said first member, means for rotating said ratchet to a position permitting engagement of said latch and first member, a pawl to prevent backward rotation of said latch, a trip to release said pawl when said first member engages said contact member, and a spring to restore said ratchet to initial position when said pawl is tripped.
23. In combination, a traveling element, a member moved thereby, a rotating element, a second member moved by said rotating element, connections between said members whereby said second member moves said first member in one direction during the normal travel of said traveling element, a contact member, means for stopping said rotating element controlled by said contact member, a latch carried by said second member and adapted to engage and move said first member into operative engagement with said contact member upon the stopping of said traveling element, a ratchet for lifting and maintaining said latch out of engagement with said first member, means for rotating said ratchet to a position permitting engagement of said latch and first member, and a spring to restore said ratchet to initial position when said pawl is tripped.
24. In combination, a traveling element, a rotating element, stop mechanism for the rotating element, a member moved by the traveling element, a member moved by the rotating element, means whereby, upon the stopping of the traveling element, both of such members are adapted to co-operate with each other to render the stop mechanism operative, a timing mechanism for controlling the co-operation of the members, and means whereby the rotating element, at the beginning of its rotation must pass through a predetermined number of revolutions before the members can so co-operate.
25. A talking machine comprising a travelling member, a rotating member, means for automatically stopping said rotating member upon the stopping of said travelling member, and means whereby said rotating member at the beginning of its operation must pass through a predetermined number of revolutions before said automatic means is rendered effective.
26. In a stop mechanism, a rotating element, a traveling element, and means adapted to co-operate with the traveling and rotating elements to actuate the stop mechanism when the traveling element ceases to travel, and means to prevent the stop mechanism from actuating during an initial period.
27. In combination, a traveling element, a rotating element, means to stop the rotating element upon the stopping of the traveling element, and means adapted to prevent the operation of the first named means, prior to a predetermined initial traverse of the traveling element.
28. In combination, a traveling element, a rotating element, means to stop the rotating element upon the stopping of the traveling element, and means adapted to render the first named means ineffective, prior to a predetermined initial traverse of the traveling element.
29. In combination, a traveling element, a rotating element, means to stop the rotating element upon the stopping of the traveling element, and means adapted to render the first named means ineffective, prior to a predetermined initial period.
30. In combination, a traveling element, a rotating element, means to stop the rotating element upon the stopping of the traveling element, and means adapted to render the first named means ineffective prior to a predetermined initial operation of the rotating element.
31. In combination, a rotating element, a traveling element, stop mechanism, a member adapted to mechanically actuate the stop mechanism upon the stopping of the traveling element, and means adapted to prevent the member from actuating the stop mechanism until after a pre-determined movement of the rotating element.
32. In combination, a rotating element, a traveling element, stop mechanism, a member adapted, through movement received from the rotating element, to actuate the stop mechanism upon the stopping of the traveling element, and means adapted to prevent the member from actuating the stop mechanism until after a pre-determined movement of the rotating element.
33. In combination, a rotating element, a

- traveling element, stop mechanism, a member under the control of the rotating element and adapted to actuate the stop mechanism upon the stopping of the traveling element, 5 and means adapted to prevent the member from actuating the stop mechanism until after a pre-determined number of revolutions of the rotating element.
34. In combination, a rotating element, a 10 traveling element, stop mechanism, a member under the control of the rotating element and the traveling element and adapted to actuate the stop mechanism upon the stopping of the traveling element, and means 15 adapted to prevent the member from actuating the stop mechanism until after a pre-determined number of revolutions of the rotating element.
35. In combination with a rotating element and a traveling element, stop mechanism for the rotating element, including a 20 rotatable member, a brake member, and a traveling member, means for operatively relating the traveling member and the brake member when the rotatable member has made a certain progression, and means for preventing the brake member from actuating until after the traveling element has ceased to travel.
36. In combination with a rotating element and a traveling element, stop mechanism for the rotating element, including a 25 rotatable member adapted to be actuated by the rotating element, a brake member, and a traveling member, means for operatively relating the traveling member and the brake member when the rotatable member has made a certain progression, and means for preventing the brake member from actuating 30 until after the traveling element has ceased to travel.
37. In combination with a rotating element and a traveling element, stop mechanism for the rotating element, including a 35 rotatable member, a brake member, and a traveling member having frictional connection with the traveling element, means for operatively relating the traveling member and the brake member when the rotatable member has made a certain progression, and 40
- means for preventing the brake member from actuating until after the traveling element has ceased to travel.
38. In combination with a rotating element and a traveling element, stop mechanism for the rotating element, including a 45 rotatable member, a detent, a brake member and a traveling member, means for connecting the traveling member and brake member when the rotatable member has made a certain progression, and means for preventing the brake member from actuating until after the traveling element has ceased to travel.
39. In combination with a rotating element and a traveling element, stop mechanism, means co-operatively related with the rotating element and the traveling element respectively, and adapted to co-operate to actuate the stop mechanism upon the stopping of the traveling element, and means to prevent such co-operation for a pre-determined initial period.
40. In combination with a rotating element and a traveling element, stop mechanism, means co-operating with the rotating element and the traveling element respectively, and adapted to co-operate to actuate the stop mechanism upon the stopping of the traveling element, and means independent of the stop mechanism adapted to prevent such co-operation.
41. In combination, record rotating means, sound reproducing means associated therewith, means for stopping the record rotating means at the completion of the record, and means preventing the operation of said last named means during the initial record playing period.
42. In combination, record rotating means, sound reproducing means associated therewith, means for stopping the record rotating means at the completion of the record, said means including an oscillation movement imparting cam, and means preventing the 95 operation of said last named means during the initial record playing period.
- In testimony whereof I have signed this specification.

LOUIS G. LARSEN.
